UNITED STATES PATENT OFFICE.

AUGUSTUS B. KINZEL, OF NEW YORK, N. Y.

SPARK-PLUG.

1,375,098.

Specification of Letters Patent. Patented Apr. 19, 1921.

Application filed July 11, 1919. Serial No. 310,081.

To all whom it may concern:

Be it known that I, AUGUSTUS B. KINZEL, a citizen of the United States, and a resident of the city of New York, county of New York, and State of New York, have invented certain new and useful Improvements in Spark-Plugs, of which the following is a specification.

The present invention relates to internal combustion engines and more particularly to spark plugs therefor. The invention has for an object to provide an improved spark plug which will not be easily broken by accidental blows in use and also to provide a spark plug having few and simple parts which can be cheaply manufactured and easily assembled.

The nature and objects of the invention will more fully appear in the following specification which should be read in connection with the drawing forming part thereof.

Figure 1 is a view in side elevation of a spark plug constructed in accordance with the invention;

Fig. 2 is a central sectional view of the same;

Fig. 3 is a top plan view thereof; and

Fig. 4 is a bottom plan view.

In the construction illustrated, the spark plug comprises a bushing 1, having a hexagonal head 2 and a threaded body portion 3, as usual. The bushing has an internal annular flange 4 engaged on opposite sides by plugs 5 and 6 of insulating material. These plugs are mounted on an electrode 7 positioned axially within the bushing and extending therethrough. The washer 8 held in place by a pin 9 thereupon and a pair of nuts 10, 11, one serving as a lock nut for the other, serve as suitable means coöperating with the electrode 7 to clamp the two insulating plugs firmly against the upper and lower sides of the flange 4, thus making a tight joint. The lower plug 6 is illustrated as made of mica. Such plug must be carefully made to present a smooth surface against the smooth lower face of the flange to insure a tight joint. Other materials may

be used but mica is preferred for the reason that the carbon which ordinarily is deposited against the cylinder head does not adhere to mica for which reason when mica is used frequent cleaning of the plug is rendered unnecessary. The upper plug 5 may be of any suitable insulating material. I

prefer to use bakelite which is found to be particularly well adapted for this use.

One of the insulation plugs is reduced and shouldered at its end to fit within the annular flange to reduce or eliminate the space between the two plugs. As shown, the lower plug is reduced and shouldered as indicated at 14. The upper plug 5 is shown as fitting into a recess 15 in the bushing and against the flange 4, this construction serving to firmly hold the plug 5 in position.

Preferably, a washer 16 of a compressible insulating material such as asbestos or the like, is introduced between the plugs in order to avoid the necessity of either making the plugs and flange with great accuracy and yet to avoid the difficulty of having an air gap between the plugs without suitable insulation between the electrode 75 and the flange of the bushing.

The lower plug is preferably relatively short and it is spaced a considerable distance from the lower end of the bushing and electrode.

A terminal 17 is secured to the lower end of the bushing and projects inwardly to provide a sparking point sufficiently close to the electrode.

Above the upper plug the electrode is surrounded by an insulating material 18 to prevent short circuit between the bushing and electrode. The material used in accordance with the present invention is soft and yielding to prevent breaking when accidentally struck with tools and the like. It may be sufficiently rigid so that it can be unscrewed from the electrode when taking apart the plug or may be soft and adhesive since it is not necessary that the plug should be taken apart for cleaning. The insulation 18 consists of a relatively soft gutta percha compound or of a bituminous material, reinforced by a fabric embedded therein or enclosing the same, as indicated at 19.

The terms "upper" and "lower" and the like, are herein used as referring to the spark plug when in the position shown in Figs. 2 and 3 of the drawing. It is to be understood the terms are used merely as a matter of convenience for the purposes of description and not as words of limitation.

I claim:

1. A spark plug comprising a bushing having an internal annular flange near its upper end, an electrode axially positioned in said bushing, an insulating plug of mica

- mounted on the electrode within the bushing and engaging the lower end of said flange, and an insulating plug mounted on the electrode engaging the upper side of said flange, 5 means on said electrode and coöperating therewith to clamp the two plugs against the opposite sides of said flange and a relatively soft yielding insulation surrounding said electrode above the insulating plugs having 10 a fabric reinforcement.
2. A spark plug comprising a bushing having an internal annular flange near its upper end an electrode axially positioned in said bushing, an insulating plug of mica 15 mounted on the electrode within the bushing and engaging the lower end of said flange, and an insulating plug mounted on the electrode engaging the upper side of said flange, means on said electrode and coöperating therewith to clamp the two plugs against the opposite sides of said flange, a compressible insulating washer between said insulat-

ing plugs, and a relatively soft yielding insulation surrounding said electrode above the insulating plugs having a fabric reinforce- 25 ment.

3. A spark plug comprising a bushing having an internal annular flange near its upper end, an electrode axially positioned in said bushing, an insulating plug of mica 30 mounted on the electrode within the bushing and engaging the lower end of said flange, and an insulating plug mounted on the electrode and engaging the upper side of said flange, means on said electrode and coöper- 35 ating therewith to clamp the two plugs against the opposite sides of said flange, and a relatively soft yielding insulation surrounding said electrode above the insulating plugs. 40

In testimony whereof I have hereunto set my hand.

AUGUSTUS B. KINZEL.
